UNITED STATES PATENT OFFICE.

WILLIAM M. BUCHNAU, OF COLUMBIA, TENNESSEE.

DESIGN FOR AN ANDIRON.

43,863.

Specification for Design.

Patented Apr. 22, 1913.

Application filed December 7, 1912. Serial No. 735,539. Term of patent 14 years.

To all whom it may concern:

Be it known that I, WILLIAM M. BUCHNAU, a citizen of the United States, residing at Columbia, in the county of Maury and the State of Tennessee, have invented a new, original, and ornamental Design for Andirons, of which the following is a specification, reference being had to the accompanying drawing, forming part thereof.

The drawing shows my new design for andirons in perspective view.

My novel design for andirons comprises a horizontal portion A, with vertical end portions B, B, and an elongated horizontal portion C extending centrally therefrom and having a downwardly extending part D, at its outer end. Rising centrally from part A, at the junction of part C therewith is a vertical member E, provided with a ball shaped part F at its upper end and on its front face with a large ring shaped member C, which large ring is the distinctive feature of the design.

I claim:

The ornamental design for an andiron, as shown and described.

WILLIAM M. BUCHNAU.
